CURRENT FAILURE ALARM

John P. Griffin, 3101 E. Old Shakopee Road,
Bloomington, Minn. 55420

Filed Nov. 29, 1972, Ser. No. 310,659

Term of patent 3½ years

Int. Cl. D29—99

U.S. Cl. D72—1 A

FIG. 1 is a front elevational view of a current failure alarm, showing my new design;

FIG. 2 is a side elevational view thereof;

FIG. 3 is a top plan view thereof; and

FIG. 4 is a rear elevational view.

I claim:

An ornamental design for a current failure alarm, as shown.
